UNITED STATES PATENT OFFICE.

BARNEY H. KLISTER AND PETER VANDEHEY, OF WRIGHTSTOWN, WISCONSIN.

DOOR-LATCH.

1,075,653.

Specification of Letters Patent. Patented Oct. 14, 1913.

Application filed April 11, 1913. Serial No. 760,489.

To all whom it may concern:

Be it known that we, BARNEY H. KLISTER and PETER VANDEHEY, both citizens of the United States, and residents of Wrightstown, in the county of Brown and State of Wisconsin, have invented certain new and useful Improvements in Door-Latches; and we do hereby declare that the following is a full, clear, and exact description thereof.

Our invention consists in what is herein particularly set forth with reference to the accompanying drawings and pointed out in the claims of this specification, its object being to provide simple, economical, strong, durable and efficient latches for swinging or sliding doors of barns and other buildings, the working of said latches being unaffected in case of vertical displacement of the doors.

Figure 1 of the drawings represents a horizontal section indicated by line 1—1 in Fig. 2, and illustrates fragments of a pair of doors held closed by a latch in accordance with our invention. Fig. 2 of said drawings represents an elevation of said fragments of doors and said latch therewith.

Referring by numerals to the drawings, 3 indicates one and 4 the other of a pair of doors that may be either swinging or sliding. Bolted or otherwise suitably secured to the sides of the door 3 are bearing plates 5, 6, for an arm terminal 7 of a hand-loop 8 having another arm terminal 9 crossing the one aforesaid at an approximate right angle thereto and designed to extend a suitable distance beyond the adjacent edge of said door when in approximately horizontal position, said loop and arms being fashioned from a single rod of suitable metal to constitute the bolt-member of our latch.

Another hand-loop 10 is shown slipped on a shouldered and screw-threaded end of the arm 7 upon which it is rigidly held by a nut 11, but other suitable means may be employed for securing said loop in working position or some other suitable handle may be detachably employed on said arm of the bolt member of the latch. It is also shown that a compensating sleeve 12 may be utilized on the arm 7 of the bolt-member of

the latch between the bearing-plate 6 and adjacent handle of said bolt-member in case the door 3 is of insufficient thickness to provide for a near approach thereto of said handle.

The bearing-plate 5 is provided at an upper corner thereof with an outer right-

angle lug 13 in which to rest the bolt-member of the latch when the same is swung up and back out of the keeper-member 14 of said latch, this keeper-member being a plate 60 fastened by screws or otherwise on the door 4 or, in case of a single door to a door post, and having an offset right angle upper end.

The arm 9 of the bolt-member of the latch is shown bent outward to form a stop-lug 85 15 that opposes the keeper-member 14 of said latch to prevent the opening of a sliding door or doors.

We claim:

1. A latch comprising a bolt-member consisting of a rod bent to form a hand-loop and crossed arms, the arms being approximately at a right-angle one to the other; bearing plates on one of the arms for attachment to opposite sides of a door, a handle in 75 detachable connection with the arm that extends through said plates, and a keeper-member for the other of said arms, the keeper being attachable to a suitable support.

2. A latch comprising a bolt-member consisting of a rod bent to form a hand-loop and crossed arms, the arms being approximately at a right-angle one to the other; bearing plates on one of the arms for attachment to opposite sides of a door, a 80 handle in detachable connection with the arm that extends through said plates, a compensating sleeve on the arm carrying the detachable handle between said handle and the adjacent bearing plate, and a keeper-member for the other of said arms, the keeper being attachable to a suitable support. 85

3. A latch comprising a bolt-member consisting of a rod bent to form a hand-loop and crossed arms, the arms being approximately at a right-angle one to the other and one of these arms bent outward at an end thereof to form a stop-lug, bearing-plates on the other of said arms for attachment to opposite sides of a door, a handle in 95 detachable connection with the arm that extends through said plate, and a keeper member for the arm having the stop-lug, the keeper being attachable to a suitable support. 100

4. A latch comprising a bolt-member consisting of a rod bent to form a hand-loop and crossed arms, the arms being approximately at a right angle one to the other; bearing plates on one of the arms for attachment to opposite sides of a door and one of the plates provided with a rest upon 110

which to swing said bolt member out of working position, a handle in detachable connection with the arm that extends through said plates, and a keeper-member for the other of said arms, the keeper being attachable to a suitable support.

In testimony that we claim the foregoing we have hereunto set our hands at Wrights-

town in the county of Brown and State of Wisconsin in the presence of two witnesses. 10
